(57) **CLAIM**

The ornamental design for a gas nozzle for a substrate processing apparatus, as shown and described.

DESCRIPTION

FIG. 1 is a front, bottom and left side perspective view of a gas nozzle for a substrate processing apparatus, showing our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a left side elevational view thereof;

FIG. 7 is a right side elevational view thereof;

FIG. 8 is a cross sectional view taken along line 8-8 in FIG. 6;

FIG. 9 is an enlarged portion view taken from encircled portion labeled, "9," in FIG. 1;

FIG. 10 is an enlarged view of FIG. 6; and,

FIG. 11 is an enlarged view of FIG. 7.

The even dashed broken lines in the drawings represent portions of the gas nozzle for a substrate processing apparatus that form no part of the claimed design.

(Continued)

The dot-dashed lines shown in FIGS. 1, 8 and 9 represent boundary lines and form no part of the claimed design.
